UNITED STATES PATENT OFFICE.

RICHARD RADDATZ, OF MILWAUKEE, WISCONSIN, ASSIGNOR, BY MESNE ASSIGNMENTS, TO WOOD HYDRAULIC HOIST & BODY COMPANY, A CORPORATION OF MICHIGAN.

DUMPING APPARATUS.

Application filed July 23, 1923, Serial No. 653,108. Renewed December 8, 1926.

This invention relates to improvements in dumping apparatus, with particular reference to apparatus for tilting vehicle bodies (box or platform) to dumping position.

In such apparatus it is of great importance that the power to be expended should be as nearly uniform as possible at all stages of the dumping operation. But the requirements for clearance, economy of space and adaptability for use in association with vehicle driving and brake mechanisms are each of such importance and conflict to such an extent, that it has heretofore been found necessary to sacrifice in whole or in part one or more of these requirements in order to satisfy the others sufficiently to produce a commercially practical structure.

The primary object of this invention is to substantially meet all of the above requirements in a single, well organized and durable structure.

More specifically stated, the object is to provide means whereby a horizontally movable member, such as the piston of a motor or jack cylinder disposed longitudinally of the vehicle underneath the platform and adjacent to its rear axle, may be so connected and associated with one or more body lifting levers also normally disposed in a nearly horizontal position, that the load ends of said levers may be raised to lift and tilt the body or platform to dumping position with a substantially constant or uniform expenditure of power and without material waste or loss of energy. In other words, the object is to provide means whereby liquid may be pumped into a horizontal motor cylinder under substantially uniform pressure while swinging substantially horizontally disposed load lifting levers from their normal position to the dumping position without developing excessive thrust strains, cramping pressures or frictional losses.

This application is a continuation of my former application, Serial Number 239,505, filed June 12, 1918, and allowed February 3, 1923.

In the drawings:—

Figure 1 is a side elevation of a motor driven truck embodying this invention with dotted lines indicating the dumping position of the body and its actuating lever.

Figure 2 is a plan view of the same with the box or platform removed.

Figure 3 is a detail view in side elevation of the controlling levers and associated parts detached and viewed from the side opposite that illustrated in Fig. 1.

Figures 4 and 5 are sectional views drawn, respectively, on lines 4—4 and 5—5 of Fig. 2.

Figures 6, 7, 8 and 9 are force diagrams.

Figure 10 is a pressure diagram or fluid pressure chart.

Like parts are identified by the same reference characters throughout the several views.

The main frame 1 of the truck is supported from the axles 2 in the ordinary manner. The box or platform 3 is supported from the tilting frame 4 by cross beams 5 and these parts 3, 4 and 5 are herein referred to as constituting the body. This body is pivotally connected with the rear end of the main frame 1 at 6, the main frame having upwardly extending projections or brackets 7 interacting with corresponding depending projections 8 on the body, the pivot shaft 6 passing through said projections. The central portion of the body is provided with depending brackets 9 in which one or more rollers 10 are journaled, the rollers being positioned to receive the pressure of the lifting levers 14 when the latter are swung upwardly.

The lifting levers 14 normally occupy a substantially horizontal position and these levers are preferably located between the main frame 1 and the tilting frame 4. Each lever 14 is provided with depending brackets 15 pivotally connected with the main frame by a cross bolt or shaft 16, which extends through one or more elements of the main frame 1 and constitutes the fulcrum or pivotal axis about which the lever swings.

In the construction shown there are two levers 14 and both of them are actuated from a fluid pressure jack or motor having a substantially horizontally disposed cylinder 18 and a piston 19 connected with the levers by a piston rod 20, cross head 21, and links 22. Two of these links 22 are preferably pivoted to each lever at 23, one on

each side of the lever, whereby the pull upon the lever is balanced. The cross head is provided with wheels or rollers 25 at its respective ends which travel upon supporting trackways 26 carried by the main frame 1, thereby relieving the piston rod 20 from cramping strain or pressure. It will be observed in Figure 4 that the piston rod extends loosely through an aperture 27 in the cross head 21 and is provided with a head piece 28 having a spherically rounded inner surface 29 socketed in the cross head, thereby forming, in effect, a ball and socket joint. The head piece has threaded engagement with the piston rod and is secured in position by the cotter pin 30. This construction allows for slight variations in the position of the cross head without transmitting cramping strains to the piston rod. It not only avoids the necessity for exact positioning of the cross head in the first instance, such as would otherwise be necessary but it also avoids the injurious effects of torsional and other strains on the cross head during load lifting operations.

Fluid under pressure is supplied to and withdrawn from the cylinder 18 by a pump 33 through the pipes or ducts 34 and 35, respectively. In the construction shown, the pump 33 delivers the power fluid to the front end of the jack cylinder through the pipe 34 to move the piston rearwardly for a load lifting operation, the fluid (preferably oil) being drawn by the pump from the rear end of the cylinder 18 through the pipe 35. A by-pass duct 36 may be utilized to allow the liquid to circulate without passing to the jack cylinder when it is desired to hold the body in a raised or partially raised position. The by-pass 36 is provided with a valve at 37 normally actuated to a closed position by a spring 38 connected with the valve actuating lever 39. This lever is automatically swung to valve opening position when the cross head 21 is at the limit of its rearward movement. A rod 40, connected with the valve lever, passes loosely through a bracket 41 on the cross head and is provided with an adjustable piece or nut 42 on its rear end. When the cross head approaches the end of its rearward stroke the bracket 41 engages the nut 42 and pulls the rod 40 rearwardly, thereby swinging lever 39 to valve opening position. The valve 37 may also be manually opened by means of the lever 44, rock shaft 44', arm 45 and link rod 46, the latter connecting lever 44 with valve lever 39.

Power to operate the pump 33 may be derived from a motor driven shaft 47 through the sprocket wheel 48, chain 49, sprocket wheel 50 and knuckle jointed shaft 51. The sprocket wheel 48 is normally loose on shaft 47 but may be coupled thereto by clutch member 53, shiftable on the shaft 47 by means of a lever 54 operating through link

55 and bell crank 56, the latter having a forked arm loosely engaging the shifting member 53.

To prevent free movement of the body 3 due to momentum or to the shifting of the load rearwardly across the main fulcrum 6 the body is preferably provided with hooks 60 which engage projections or studs 61 at the forward or upper ends of the levers 14 when the latter are at the limit of their upward stroke. The levers are preferably provided at these ends with rounded or beveled "run-off" bearing surfaces 62 adapted to allow the body to gradually come to rest during the final lifting movement of the levers. 80

The mode of operation is as follows: Assuming the center of gravity of the load to be at the point g (Figures 1 and 6), and the engine running, the operator may dump the load by merely raising lever 54, thereby coupling sprocket wheel 48 with the engine driven shaft 47. Motion will thereupon be transmitted to operate the pump 33, which may be assumed to be an ordinary rotary pump. As the pressure builds up in front of the piston 19, the initial movement of the latter, after taking up the so-called "slack", is applied to the load as indicated in Figure 6 in which the distance $c-d$ indicates the length of the moment arm of the lever 14 95 and the distance $c-e$ indicates the distance of the load from the fulcrum. The load g is in a vertical plane through the points c at which the power is applied to the body and therefore the distance from the main 100 or body fulcrum 6 is not material while the parts are in that position.

But it is obvious that as soon as the body commences to lift, the load g (center of gravity) is shifted toward the vertical plane 105 through main fulcrum 6 slowly at first and then in a relatively accelerating ratio as its are of movement approaches a horizontal direction. The effect of this is at first more than counteracted by the lengthening of the 110 load arms of levers 14, which act at a shorter radius. But as the levers 14 move upwardly, the links 22 swing toward the horizontal plane of piston rod 20 thereby increasing the length of the moment arm, i. e., the effective radius at which the power is applied to the levers, and this prevents the levers from being subjected to a peak load during the first quarter of their stroke. 115

With all features taken into consideration, it is possible to tilt the load carrying body from normal to dumping position, with a substantially uniform or slightly increasing expenditure of power, as represented by the pressure of fluid in the jack cylinder and as indicated by the pressure diagram shown in Figure 10. During the final stages, when the center of gravity g is most rapidly approaching the vertical plane of the pivot shaft 6, the load arms of levers 14 are not 120 125 130

only lengthened, but the moment arm is shortened as shown in Figure 9.

During the load lifting movement, the operator retains full control, not only through the clutch operating lever 54 but also through the lever 44, which enables him to by-pass the pumped liquid in whole or in part, at any stage. The load may be partially dumped, and the vehicle moved before completing the dumping operation. The body may be lowered by opening the by-pass and stopping the pump, or it may, if desired, be lowered by fully opening the by-pass while the pump is in operation, this being dependent, of course on the relative capacity of the by-pass to that of the pump and its supply and delivery passages.

The piston rod is relieved of lateral or cramping strain by the cross head and its associated supports. Friction of the cross head on its supports is reduced to a minimum by the anti-friction rollers 25. By locating the jack cylinder and cross head a substantial distance above the main frame 1 these parts are protected and the clearance of the vehicle for passage over obstructions in the roadway is in no way affected by the presence of the operating mechanism. This location of the cylinder and cross head also makes it possible to position the levers 14 above the main frame, and their fulcrum pivots 16 above the lower margins of the frame at a point where these fulcrum pivots 16, the pivotal connections 23 of the links 22 and the bearing points of the rollers 10 on the levers 14 will be substantially in a line at an angle of nearly 45° from the horizontal plane of the main frame. The links 22 normally stand at an angle nearly perpendicular to said line; whereby the pivot bearing 16 is almost wholly relieved from resultant axial thrust pressures. There is a little loss of power due to the resultant pressure of the rollers 25 on their associated trackways, but this is negligible.

The frame 4 is constructed and supported from the main frame 1 in such a manner that the cylinder may be located above the pivot shaft 6 (main fulcrum 6 in Figures 6 to 9) and the pivot shaft or pins 16 of the lifting levers 14 may be located substantially above the rear axle of the vehicle, the levers swinging upwardly and rearwardly with the body, and the connections between the piston and the levers, being tension connections. This arrangement allows the rear end portions of the levers 14 to act initially upon the load directly underneath its center of gravity and at but a short distance in front of the rear axle, the center of gravity of the normal load being located between the front and rear axles but as near to the rear axle as is consistent with stability under varying load carrying and dumping conditions. The arrangement of the dumping

mechanism as above described also allows a lever movement in the same direction that the body tilts. This is also a feature of great importance in avoiding power losses.

With the mechanism above described, the speed of the vehicle engine and of the pump may be kept substantially constant, the resistance offered by the liquid in the jack cylinder being substantially constant. Therefore, a slow steady body tilting movement is possible, strains may be accurately calculated in advance and the necessary strength required in the various structural parts much more definitely determined than in dumping mechanisms as heretofore constructed.

I claim:—

1. In an oscillatory hoisting mechanism, a frame, a motor thereon, a body oscillatory with respect to said frame, a lever oscillatory with respect to the frame and operatively associated with the body to move the same with variable mechanical advantage, and linkage connecting said motor with said lever for the oscillation thereof with mechanical advantage variable inversely to the first mentioned mechanical advantage.

2. In an oscillatory hoisting mechanism, a frame, a motor thereon, a body oscillatory with respect to said frame, a lever oscillatory with respect to the frame and operatively associated with the body to move the same with variable mechanical advantage, and linkage connecting said motor with said lever for the oscillation thereof with mechanical advantage variable inversely and substantially proportionately to the first mentioned mechanical advantage.

3. In an oscillatory hoisting mechanism, a frame, a motor thereon, a body oscillatory with respect to the frame, a lever oscillatory with respect to the frame and operatively associated with the body to move the same by the exertion of the power from progressively varying distances from the lever fulcrum as the lever swings, and motion transmitting mechanism including a link connecting said lever with said motor adapted to transmit power to the lever with a mechanical advantage variable inversely to the first mentioned mechanical advantage.

4. In a dumping mechanism, the combination with a support, of a body pivotally connected with the support and having a depending bearing substantially below its center of gravity when the body is in normal position, a lever fulcrumed on the support in advance of the body pivot and movable in the general direction of body tilting movement, said lever when moved, being adapted to engage said bearing at progressively increasing distances from its fulcrum, whereby the lever may act upon the body with variable mechanical advantage, and means for applying power to said lever at a progressively increasing effective radius during the

initial body lifting movement of the lever, whereby the means for applying power to the lever acts with mechanical advantage variable inversely to the first mentioned mechanical advantage.

5. In a dumping mechanism, the combination with a support, of a body pivotally connected with the support, a lever fulcrumed on the support to move the body, means for transmitting power from the lever to the body at progressively varying distances from the lever fulcrum as the lever swings, a lever actuating member mounted on the support, and a link connection between said member and the lever adapted to extend the effective radius at which power is supplied to the lever during the initial stages of its body lifting movement, whereby to compensate for the increase in distance from the lever fulcrum at which the lever acts upon the body as the latter tilts.

6. In a dumping mechanism, the combination with a support, of a load carrying body, a body actuating lever, said lever and body having spaced fulcrum connections with the support, a motor for transmitting power to the lever, means for permitting the lever to act upon the body with variable mechanical advantage, and means for transmitting power from said motor to the lever adapted to vary the mechanical advantage with which power is transmitted from the motor to the lever inversely and substantially in proportion to the variation in the said first mentioned mechanical advantage.

7. The combination with a motor driven vehicle having a main frame, of a load carrying body fulcrumed for tilting movement from a normal load carrying to a dumping position, a lever pivoted to said frame, a lever actuating member movable substantially in a horizontal plane and having inclined link connection with said lever, and a bearing on the body against which said lever initially bears substantially in a line extending from the lever pivot through the point of link engagement with the lever, the arrangement being such that the lever and the body may be swung in the same direction for a dumping operation and the link connection simultaneously moved toward the horizontal plane of movement of the lever actuating member.

8. The combination with a motor driven vehicle having a main frame, of a load carrying body pivotally connected near its rear end with said frame, a normally horizontal body tilting lever having its rear end connected with the frame, a hydraulic motor having a horizontally disposed cylinder supported by the frame between it and said body and provided with a piston having a forwardly extending piston rod, forwardly and normally downwardly inclined linkage connecting the piston rod

with the lever and adapted to swing the lever, including that portion of the same to which the linkage is connected, upwardly and rearwardly to tilt the body to dumping position.

9. Dumping mechanism including the combination with a load carrying body fulcrumed for tilting movement from a normal load carrying to dumping position, of a body tilting lever normally substantially horizontal and fulcrumed to swing in the same direction as the body, a bearing on the body normally substantially below its center of gravity and adapted to be continuously engaged by said lever during a tilting movement, a horizontally movable, fluid actuated member located above the lever and having inclined link connection therewith at a point between the lever fulcrum and the point of engagement with the load.

10. Dumping mechanism including the combination of a main frame, a load carrying body pivotally connected with the main frame, a body tilting lever pivotally connected with the main frame on an axis parallel with and in advance of the body connection, said lever being adapted to swing upwardly and in the direction of body tilting movement, and lever actuating mechanism located between said pivotal axes and between the main frame and the body.

11. The combination with the main frame of a vehicle, of a tilting body pivoted thereto and adapted to swing from load carrying to dumping position, a body actuating lever pivoted to the main frame and adapted to swing in the direction of body tilting movement, a lever actuating device movable in the space between the main frame and the load supporting portion of the body and having downwardly and forwardly extending link connection with the lever, and a carriage movably supported by the main frame in supporting relation to the power receiving end of said link connection.

12. The combination with the main frame of a vehicle, of a body pivoted thereto at its rear end and adapted to be tilted from load carrying to dumping position, a lever having its rear end portion pivotally connected to the frame in advance of the body pivot and normally disposed in a substantially horizontal position, a fluid actuated member movable in the space between the lever and body pivots and between the main frame and the load carrying portion of the body, tension connections between said member and the lever, and a bearing carried by the body in the path of the lever in advance of said tension connections and adapted to receive pressure engagement of the lever in all stages of the body tilting movement, said lever being located at a substantial distance below the level of the fluid

actuating member and said bearing on the body, being normally substantially in an oblique line extending from the lever pivot through the point where said tension connections engage the lever.

13. The combination with a vehicle having a motor driven shaft, a main frame provided with a tilting body, a lever for actuating said body operable in the space above the main frame, a hydraulic jack having a cylinder disposed substantially horizontally and provided with a lever actuating piston rod, a carriage loosely supporting the outer end of the piston rod and adapted for movement longitudinally along said frame, link connections between the carriage and the lever, a pump having supply and delivery connections with the respective ends of said jack, a by-pass between said connections, a valve for controlling said by-pass, means for actuating the pump from said motor driven shaft, and means connected with said carriage for actuating said valve to by-pass the pumped liquid from the delivery to the

supply side of the pump connections at a predetermined stage of carriage movement.

14. In a dumping vehicle the combination with a supporting frame, of a dumping lever pivoted thereto and normally disposed in a substantially horizontal position, a hydraulic jack having a piston rod linked to said lever, a carriage supporting said piston rod from the main frame, a pump, fluid supply and exhaust connections between the respective ends of the jack and said pump, a by-pass having a valve controlling delivery of fluid from the delivery to the supply side of said pump, a lever for actuating said valve, means for normally actuating said lever to valve closing position, means for manually actuating said lever to valve opening position, and actuating connections between the carriage and said lever adapted at a predetermined stage in the movement of said carriage to automatically swing said lever to valve opening position.

RICHARD RADDATZ.
